UNITED STATES PATENT OFFICE.

JOHN B. GURY, OF ST. LOUIS, MISSOURI.

GRINDER FOR CLOTH-CUTTING MACHINES.

1,150,265.

Specification of Letters Patent. Patented Aug. 17, 1915.

Application filed April 8, 1915. Serial No. 20,065.

To all whom it may concern:

Be it known that I, JOHN B. GURY, a citizen of the United States, and a resident of the city of St. Louis and State of Missouri, have invented a new and useful Improvement in Grinders for Cloth-Cutting Machines, of which the following is a specification.

This invention relates to grinders for sharpening the cutters of cutting machines, particularly cloth cutting machines.

One object of the invention is a grinder for a cloth cutting machine which is normally positioned some distance above the cutter so as to be out of the way and not interfere with the ordinary operation of the machine, and which grinder can be easily and quickly manipulated to grind the cutter.

Further objects of the invention relate to the details of the construction which are more fully set forth hereinafter.

Generally stated, the invention resides in a grinder which has two grinding wheels movably supported on the standard of a cloth cutting machine and which is provided with a device for moving said grinding wheels from their inactive position (where they are out of the way and do not interfere with the ordinary operation of the machine) to their grinding position, and for controlling the force with which they are pressed against opposite faces of the cutter.

The invention further consists in the parts and in the arrangements and combinations of parts, more fully set forth hereinafter.

In the accompanying drawings which form part of this specification and in which like reference characters refer to like parts in the several views, Figure 1 is a side view of a cloth cutting machine having a grinder embodying the invention attached thereto, the parts of said grinder being shown in their normal inactive position; Fig. 2 is an end view of the same machine, also showing the grinder in its inactive upper or normal position; Fig. 3 is a fragmentary side view of the same showing the parts of the grinder in its lower or grinding position; Fig. 4 is a fragmentary end view of the same showing the parts of the grinder in its lower or grinding position; Fig. 5 is a rear view of the grinder detached from the machine; Fig. 6 is a horizontal section on the line 6—6 in Fig. 1, showing the adjustable support for the grinder; Fig. 7 is a perspective view of the clip for securing the upper end of the

spring which normally holds the grinding wheels in their upper inoperative position; and Fig. 8 is a cross-section of a grinding wheel on the line 8—8 in Fig. 5.

Referring to the accompanying drawings, the cloth cutting machine comprises a foot-plate 1, the edges of which are thin so that said foot-plate may be easily slipped and guided under a pile of cloth. Secured to the foot-plate 1 is a standard 2 which constitutes the body structure of a cloth cutting machine and supports the rotary cutter 3 and the motor for driving said cutter. The motor is mounted in a casing 4 and is connected to the cutter 3 by suitable gearing. The motor and the gearing form no parts of the present invention and are not shown in detail.

The grinder comprises a supporting member 5 which is adjustably secured at its lower end to the standard of the machine by means of a horizontal pin 6. The pin 6 is circular with one face thereof slightly flattened, and it fits in a horizontal hole in the standard 2 and is held in its different adjusted positions by a set-screw 7, which is screw-threaded in the standard and engages the flattened face of said pin. The pin 6 preferably projects through the supporting member 5 and beyond the front face thereof to constitute a pivot stud upon which are pivotally mounted two arms 8. A screw 9 holds the arms 8 in place on the end of the pin. Two pins 10 are fastened to the arms 8 at the outer ends thereof by means of screws 11. Grinding wheels 12 are journaled on the pins 10. Each grinding wheel 12 is preferably clamped on a bushing 13 which is retained on the pin 10 by means of a screw 14. The bushing has a circular head at one end which cooperates with a nut 15 screw-threaded on the opposite end to hold the grinding wheel. The head of the bushing has a pin 16 on its inner side which fits into a hole in the grinding wheel to hold it from rotation on the bushing. Washers 17 are interposed between the nut 15 and the grinding wheel to accommodate grinding wheels of different widths. The arms 8 are journaled on the pin 6 one alongside of the other, and the inner arm has its outer end offset inwardly, in consequence of which the grinding wheels 12 are mounted in different planes and engage different points on the periphery of the cutter in grinding position.

The upper end portion of the supporting

member 5 extends horizontally forward, and terminates in a hook-shaped finger piece 18, by which the cloth cutting machine may be guided or lifted. This horizontally extending portion of the supporting member 5 has a vertical circular hole through it in which is slidably mounted an operating rod 19. The operating rod 19 is bifurcated at its lower end, between which bifurcations are fitted the upper ends of two links 20 which are pivotally connected to said operating rod by a pin 21. The lower ends of the links 20 are pivotally connected to the arms 8 near the middles thereof. The supporting member 5 has a vertical slot 22 near its lower end in which the inner end of the pin 21 is guided. The lower end of said slot 22 is enlarged, in order that the pin 21, when it is near the lower end of said slot, may move sidewise relatively to the supporting member 5 to a limited extent. Encircling the operating rod 19 is a tension coil spring 23, the lower end of which is fixed to the pin 21 and the upper end of which is engaged by a clip 24 which hooks over the horizontally extending portion of the supporting member 5. On the rear face of the supporting member 5 near the upper end of the slot 22 is a cushion spring 25 which extends downwardly below the upper end of said slot in position to be struck by the pin 21 in its raised position. A finger piece 26, preferably of hardened rubber or similar material, is secured to the upper end of the operating rod 19.

The operation of the grinder is as follows: When the parts are in their normal or inoperative position, the arms 8 extend upwardly above the lower end of the supporting member 5, and the operating rod 19 is in its uppermost position. The grinding wheels 12 are drawn up adjacent to the supporting member 5 on opposite sides thereof and are located so as not to interfere with the ordinary operation of the cloth cutting machine. As shown most clearly in Figs. 4 and 5, one vertical edge portion of the supporting member 5 is partly cut away to afford space for the adjacent grinding wheel. To sharpen the cutter 3, the motor is started and said cutter is rotated, and while the cutter is rotating, the operator presses downwardly on the finger piece 26 and pushes the operating rod 19 down, against the opposition of the spring 23. The links 20 which are connected to the operating rod 19 swing the arms 8 and the grinding wheels 12 carried thereby downwardly so that said grinding wheels press against the cutter 3 on opposite faces thereof. The circumferential edge portion of the cutter is preferably beveled on one side, and one grinding wheel presses against this beveled portion of the cutter near the edge of said cutter, and the other grinding wheel presses against the flat

face of the cutter near its edge. The grinding wheel which presses against the beveled edge portion of the cutter is preferably made of a material which is more abrasive in its action than the other grinding wheel. The first or hardest grinding wheel operates to sharpen the cutter, and the other grinding wheel removes the bur formed during the sharpening operation.

As hereinbefore described, the grinding wheels 12 are arranged in different planes, and in order that said grinding wheels may press against the cutter 3 near the outer edge thereof, the arm 8 for the outer grinding wheel is longer than the other arm. The circumferential faces of the grinding wheels 12 are beveled to bear properly against the cutter. The axes of the grinding wheels 12 are arranged at an angle to the radius of the cutter at the point where said grinding wheels press against said cutter, and consequently as the cutter rotates the grinding wheels rub against the cutter and are rotated slowly thereby. The pressure of the grinding wheels 12 on the cutter is uniform regardless of the size of the grinding wheels, since the arms 8 and the links 20 are movable, and when one grinding wheel strikes the cutter its arm forms a fulcrum about which the arm of the other grinding wheel may swing. Consequently, although one of the grinding wheels may wear smaller than the other, both grinding wheels will press against the cutter. After the cutter has been subjected to several grinding operations it becomes so small that the grinding wheels will not press against it in a proper place to grind the cutting edge of said cutter. In order to bring the grinding wheels into proper position, the set-screw 7 is loosened and the pin 6, together with the supporting member 5 and the other parts of the grinder connected thereto, are moved toward or away from the standard 2 of the machine. It may be desirable to provide another hole 27 in the standard 2 for the pin 6, in order to provide sufficient adjustment for grinding small cutting wheels. When the cutter has been sufficiently ground, the operator merely relaxes downward pressure upon the finger-piece 26 and the operating rod 19, and the spring 23 returns the arms 8 and the grinding wheels 12 to their upper position where they are out of the way and do not interfere with the operation of the machine.

The construction shown and hereinbefore described may be considerably modified without departing from the invention, and I do not wish to be restricted to the details of the construction shown and described.

What I claim is:

1. A cloth cutting machine comprising a foot-plate and a standard, a rotary cutter journaled on said standard, a supporting

- member adjustably secured to said standard, two arms pivotally connected to said supporting member at a point above said cutter and on axes spaced substantially at right angles to the axis of said cutter, grinding wheels rotatably mounted at the outer ends of said arms, and means for swinging said arms downwardly to bring said grinding wheels into contact with said cutter on opposite faces thereof, said supporting member being adjustable in the direction parallel with the axis of pivotal connection of said arms therewith.
2. A cloth cutting machine comprising a foot-plate and a standard, a rotary cutter journaled on said standard, two arms pivotally connected to said standard at a point above said cutter, grinding wheels mounted on said arms, a vertically movable operating rod, links connecting said operating rod to said arms, and resilient means for holding said operating rod in its uppermost position.
3. A cloth cutting machine comprising a foot-plate and a standard, a rotary cutter journaled on said standard, a supporting member adjustably secured to said standard, two arms pivotally connected to said supporting member, grinding wheels rotatably mounted on the outer ends of said arms, an operating rod slidably mounted on said supporting member, and movable links pivotally connected to said arms and to said operating rod.
4. A cloth cutting machine comprising a foot-plate and a standard, a cutter movably mounted on said standard, a supporting member adjustably secured to said standard and having a vertical slot therein, two arms pivotally connected to said sup-
- porting member, grinding wheels rotatably mounted on said arms, an operating rod slidably mounted on said supporting member and guided thereby at its upper end and having a pin at its lower end guided by said slot, said slot at its lower end being wider than said pin, and movable links pivotally connected to said arms and to the lower end of said operating rod.
5. A cloth cutting machine comprising a foot-plate and a standard, a cutter rotatably mounted on said standard, a supporting member adjustably secured to said standard, two arms pivotally connected to said supporting member to swing at right angles to the plane of said cutter, grinding wheels rotatably mounted on said arms, and means for swinging said arms simultaneously, said means comprising pivotal links connected to the respective arms for equalizing the pressure of said grinding wheels against said cutter.
6. A cloth cutting machine comprising a foot-plate and a standard, a rotary cutter journaled on said standard, a supporting member adjustably secured to said standard, two arms pivotally connected to said supporting member, grinding wheels rotatably mounted on the outer ends of said arms, an operating rod slidably mounted on said supporting member, movable links pivotally connected to said arms and to said operating rod, and equalizing means connecting said links whereby grinding wheels of different sizes may operate simultaneously.

Signed at St. Louis, Missouri, this 5th day of April, 1915.

JOHN B. GURY.
